H. IVEN.
PORTABLE FENCE.
APPLICATION FILED JAN. 14, 1914.

1,114,479.

Patented Oct. 20, 1914.

UNITED STATES PATENT OFFICE.

HENRY IVEN, OF CHICAGO, ILLINOIS.

PORTRABLE FENCE.

1,114,479.

Specification of Letters Patent. Patented Oct. 20, 1914.

Application filed January 14, 1914. Serial No. 812,090.

To all whom it may concern:

Be it known that I, HENRY IVEN, a subject of the Emperor of Germany, residing at Chicago, in the county of Cook, State of Illinois, have invented certain new and useful Improvements in Portable Fences; and I do hereby declare the following to be a full, clear, and exact description of the invention, such as will enable others skilled in the art to which it appertains to make and use the same.

The present invention is directed to portable fences, and has for its object to so construct a device of this character that the same can be easily and quickly folded for transportation.

A further object of the invention is to provide a fence of this character so constructed that the same can be readily attached to the ends of railway ties at places so as to prevent persons from passing from one track to another.

With these and other objects in view, this invention resides in the novel features of construction, formation, combination and arrangement of parts to be hereinafter more fully described, claimed and illustrated in the accompanying drawing, in which:

Figure 1 is a side elevation of the fence. Fig. 2 is a sectional view on line 2—2 of Fig. 1. Fig. 3 is a sectional view on line 3—3 of Fig. 1. Fig. 4 is an end view of one of the uprights and the supporting base folded.

Referring to the drawing, the numeral 1 designates a complete section, any number of which may be used as the occasion may require, and in the present instance a pair of complete sections are shown.

Each section comprises an upright or post 2 to the lower end of which is hingedly connected a bar 3, said bar having formed therein screw openings 4 and 5, so that when said bar is resting upon the tie 6, the same may be rigidly connected thereto upon passing screws 7 through said openings. To hold the

uprights 2 in their proper vertical position a brace bar 7' is provided, and has its upper end hingedly connected intermediate the ends of the upright, and its lower end provided with an off-set 8 having formed therein an opening 9, which registers with the screw opening 5 so that the screw which aids in attaching the bar 3 to the tie, also serves to attach the off-set 8 to the bar. Each section further consists of a plurality of hingedly connected panels 10, the outermost panel of each section being provided with hooks 11, the bills of which being adapted to detachably engage the pins 12 carried by the uprights or post 2.

It is obvious that the panels can be readily removed from engagement with the uprights and as the same are hingedly connected they may be rolled into a compact form, and it will be further noted that as shown in Fig. 4 that the upright, supporting bar and brace can be readily folded so as to occupy a minimum amount of space.

What is claimed is:

A fence of the class described comprising a plurality of sections, each section comprising an upright, a bar having openings formed therein, said bar being adapted to engage a supporting tie, said bar having one end pivotally connected to the lower end of the upright, a brace bar having its upper end pivotally connected to the uprights, and its lower end provided with an off-set having an opening formed therein for registry with one of the openings of the bar, securing devices passed through the opening in the off-set and openings in said bar for attaching the bar to the supporting tie, and hingedly connected panels detachably connected to the uprights.

In testimony whereof, I affix my signature, in the presence of two witnesses.

HENRY IVEN.

Witnesses:

R. A. ALLEN,
CLARENCE E. KENNEY.
